United States Patent Office

Des. 217,140
Patented Apr. 14, 1970

217,140

RESTAURANT AND COCKTAIL LOUNGE BUILDING

Robert H. Spain, Fort Lauderdale, and Sidney R. Wilkinson, Bradenton, Fla., assignors to Chris McGuire Inc.,
Fort Lauderdale, Fla., a corporation of Florida

Filed June 24, 1969, Ser. No. 17,849

Term of patent 14 years

Int. Cl. D25—04

U.S. Cl. D13—1

FIG. 5

FIG. 4

FIG. 1 is a perspective view of the restaurant and cocktail lounge building showing our new design;

FIG. 2 is a front elevation view of the building shown in FIG. 1;

FIG. 3 is a side elevation view of said building;

FIG. 4 is an elevation view of the other side of said building;

FIG. 5 is an elevation view of the back of said building; and

FIG. 6 is a top plan view of said building.

We claim:

The ornamental design for a restaurant and cocktail lounge building, as shown and described.
